(57) **CLAIM**

The ornamental design for a modular light fitting, as shown and described.

DESCRIPTION

FIG. 1 is a front declined perspective view of a first embodiment of a modular light fitting;

FIG. 2 is an elevated perspective view of the first embodiment of the modular light fitting depicted in FIG. 1;

FIG. 3 is a front view of the first embodiment of the modular light fitting depicted in FIG. 1;

FIG. 4 is a back view of the first embodiment of the modular light fitting depicted in FIG. 1;

FIG. 5 is a right side view of the first embodiment of the modular light fitting depicted in FIG. 1, where the left side view is a mirror image of FIG. 5;

FIG. 6 is a top view of the first embodiment of the modular light fitting depicted in FIG. 1;

FIG. 7 is a bottom view of the first embodiment of the modular light fitting depicted in FIG. 1;

FIG. 8 is an elevated perspective view a second embodiment of the modular light fitting;

FIG. 9 is a declined perspective view a second embodiment of the modular light fitting;

FIG. 10 is a front view of the second embodiment of the modular light fitting depicted in FIG. 8;

FIG. 11 is a right side view of the second embodiment of the modular light fitting depicted in FIG. 8;

FIG. 12 is a left side view of the second embodiment of the modular light fitting depicted in FIG. 8;

FIG. 13 is a top view of the second embodiment of the modular light fitting depicted in FIG. 8;

FIG. 14 is a bottom view of the second embodiment of the modular light fitting depicted in FIG. 8;

FIG. 15 is a declined perspective view of a third embodiment of a modular light fitting;

FIG. 16 is exploded view of the third embodiment of the modular light fitting depicted in FIG. 15;

FIG. 17 is an elevated perspective view of the third embodiment of the modular light fitting depicted in FIG. 15;

(Continued)

FIG. 18 is an exploded view of the third embodiment of the modular light fitting depicted in FIG. 17;
 FIG. 19 is a front view of the third embodiment of the modular light fitting depicted in FIG. 15, where the back view is a mirror image of FIG. 19;
 FIG. 20 is an exploded view of the third embodiment of the modular light fitting depicted in FIG. 19; and,
 FIG. 21 is a right side view of the third embodiment of the modular light fitting depicted in FIG. 15, where the left side view is a mirror image of FIG. 21.
 The broken lines in the figures represent portions of the article which form no part of the claimed design.
